UNITED STATES PATENT OFFICE.

CHARLES A. HOLLAND, OF FAYETTEVILLE, NORTH CAROLINA.

HARNESS-MAKER'S STITCHING-HORSE.

SPECIFICATION forming part of Letters Patent No. 225,604, dated March 16, 1880.

Application filed October 11, 1879.

To all whom it may concern:

Be it known that I, CHARLES A. HOLLAND, of Fayetteville, in the county of Cumberland and State of North Carolina, have invented 5 certain new and useful Improvements in Harness-Makers' Stitching-Horses; and I do hereby declare that the following is a full, clear, and exact description of the construction and operation of the same, reference being had to the 10 annexed drawings, making a part of this specification, and to the letters and figures of reference marked thereon.

Figure 1 of the drawings is a representation of a side elevation of my harness-maker's 15 stitching-horse. Fig. 2 is a plan view of the same. Fig. 3 is a front view. Figs. 4, 5, and 6 are detail views, and Figs. 7 and 8 are views of modifications.

The nature of this invention relates to harness-makers' stitching-horses.

My improvement consists in the construction and arrangement of parts, as will be fully set forth in the following description, and particularly pointed out in the claims.

25 In the drawings, A designates the operating-lever, composed of two bars bolted together. The foot-rest is set at the required angle by adjusting one of the bolts or screws in holes formed in one of the bars, as shown. 30 The lever A connects with an arm upon shaft B by means of a toggle-joint, and the shaft B is provided with a spring which throws back the operative mechanism of the machine after a forward stroke of the same.

35 C designates a pivoted lever-bar, which is mounted upon a slide, D, and operated by a crank-arm upon the shaft B. This lever-bar carries the tack-extractor E in rear of the slide D, and is arranged so as to operate the needle F.

The needle-carrier G and the slide D are either formed in one piece or united together, so as to have during operation a simultaneous movement.

45 The tack-extractor, which is designed to extract tacks from the straps before they are fed between the jaws of the vise, is composed of two plates secured to the sides of the lever C, and curled inward at their lower edges, so as to 50 catch under the heads of the tacks and withdraw the same from the leather as the rear end

of the lever is elevated by the crank-arm of the shaft B.

H designates the feed device, which is formed with a lug or projection, h, which is arranged to work in a slot, I, formed in the slide D. The feed device H, which is serrated upon its under side, approximates in form to two wedges, having a taper from its forward end to the lug h, and also a taper from the lug to its rear extremity, there being, as shown, an increased thickness at the central part, where the lug is located.

K designates a set-screw arranged to pass through the short standard of the slide, upon which the lever C is pivoted. As the slide and carrier are thrown forward this set-screw strikes against the lug h, and hence it is made adjustable, so as to determine the movement of the feed.

L represents a spring, which is secured to one of the clamping-jaws of the vise, and which engages with lug h so as to control the feed.

M N designate the two hinged jaws of the vise, and O a board in which a plate to which these jaws are hinged is secured. Both of these jaws are recessed, and each jaw carries a spring. As herein shown the spring in the jaw M is considerably shorter than the one in the remaining jaw.

P designates a pin, which is secured to the spring q in jaw M by nuts; and Q, a block secured to the inner face of jaw N and formed with a hole, through which the pin is arranged to pass when the jaws are brought together. 85 After the jaws are thus closed a screw, R, is passed through the jaw N and its long spring and screwed into the end of the pin P, thereby holding the jaws together. In this way spring-jaws are attained which will open sufficiently 90 to allow of the free passage of the straps or traces which are being sewed, and which will readily yield to any crimps in the leather.

By means of the nuts which secure the short spring upon the pin the spring force may be 95 regulated to suit the work to be done.

S designates a thumb-screw arranged to work in the block Q, and adapted to open the jaws, being provided with a pin, T, which, when the thumb-screw is turned in one direction, bears against the jaw M, and hence opens the two jaws. When turned in the other di-

rection the jaws will automatically close together.

U U designate bars, which are secured to the jaw M, and these bars are formed with 5 bearings for the shaft B.

V represents an angular-shaped bar carrying the guide and friction rollers V' V', and W a guide, which, like the bar V, which carries the rollers, is made adjustable. For this 10 purpose the roller-bar V and the bar which carries the guide are slotted, and both connected to one of the bars U by a thumb-screw. At each forward stroke of the lever a trace or straps to be sewed will be fed forward between the jaws just one stitch. When the 15 feed reaches its forward limit the lever-bar, which carries the tack-extractor, and which has forced forward the carrier and slide, and consequently the feed, actuates the needle and causes the same to pass through the leather.

The machine is to be fastened on a bench and worked by foot, the sewing being done by hand through the holes made by the needle or awl.

25 In Figs. 7 and 8 of the drawings I have shown one of the jaws provided with devices for so moving the strap-guides that during operation of the hereinbefore-described mechanism the strap will be punctured by the awl in a wavy line. Such devices consist of a flat bar, 1, which is pivoted upon the pin 2 at one end, and adapted at its remaining forked end to engage with a pin, 3, upon the slide which unites with the awl-carrier.

30 Within a recess in the jaw and below the bar 1 is a ratchet-wheel, 4, which is rigidly secured upon the pin 3, and upon the under side of bar 1 is a spring-pawl, arranged to engage with the said ratchet. Upon the other side of 35 the jaw is a wheel, X, formed with a cam-groove and secured upon pin 3, and in this groove works the pin 4, secured to a cross metal strap, 5.

In practice I propose connecting straps 45 and 6 with the bars 7 and 8, the latter of which carries the guide W. I also arrange bars 9 and 10 so as to work in guides 11, and to these I also secure the straps 5 and 6.

50 At each forward movement of the needle guide and carrier the movement of the bar 1 will cause the spring-pawl which it carries to engage with the ratchet-wheel and turn the same. This also causes a movement of the wheel having a cam-groove, whereby the bars will be moved and the position of the guide changed. A succession of such movements causes the guide for the strap to move gradually away from the jaws, and then to gradually

move backward toward the same, whereby the punctures in the leather will be in a wavy or 60 serpentine line. The curves of the line may be varied by changing a different cam-wheel for the one shown.

These devices are incorporated in the machine without displacing the springs hereinbefore described; and to the intelligent mechanic 65 the arrangement of parts to effect such result will be apparent.

Having thus described my invention, what I claim, and desire to secure by Letters Pat- 70 ent, is—

1. In a harness-maker's stitching-horse, the lever A, composed of the two bars bolted together and adapted to be adjusted relatively to each other so as to set the foot-rest at a 75 suitable angle by means of the adjustment of one of the bolts in holes formed in one of the bars, substantially as herein set forth.

2. In combination with the sliding awl or 80 needle carrier and feed device, the tack-extractor secured upon the lever which actuates the needle-bar, substantially as shown and set forth.

3. The awl or needle carrier G, having a slotted slide, D, in combination with the feed 85 device H, with lug h, the lever C, and adjustable set-screw K, substantially as set forth.

4. The feed device H, formed with lug h, and having the herein-described double wedge-shaped conformation, as shown and specified. 90

5. The adjustable roller-bar V, carrying the rollers V', and the adjustable guide W, arranged as shown, and in connection with a sliding awl-carrier and feed device, as set forth. 95

6. In combination with the jaws and springs, the pin P and thumb-screw S, as specified.

7. The jaws M N, one provided with a long spring and the other with a spring of less length, in combination with the pin P, secured 100 to one of the springs by nuts and to the remaining spring by a screw passed through the jaw and spring, substantially as shown and specified.

8. The arm or bar 1, engaging with a pin 105 upon the awl-carrier slide, the pawl on the said bar, the ratchet-wheel 4, pin 3, wheel X, with cam-groove, and the sliding bars with the strap-guide, all arranged as set forth.

In testimony that I claim the above I have 110 hereunto subscribed my name in the presence of two witnesses.

CHARLES A. HOLLAND.
